CLAIM

The ornamental design for a nightlight and air sensor, as shown and described.

DESCRIPTION

FIG. 1 is a front side perspective view of a nightlight and air sensor;

FIG. 2 is a bottom view thereof;

FIG. 3 is a left side elevation view thereof;

FIG. 4 is a rear elevation view thereof;

FIG. 5 is a front bottom perspective view thereof;

FIG. 6 is a right side elevation view thereof;

FIG. 7 is a front elevation view thereof;

FIG. 8 is a top elevation view thereof;

FIG. 9 is a rear bottom perspective view thereof;

FIG. 10 is a rear top perspective view thereof; and,

FIG. 11 is a rear bottom perspective view thereof.

All features illustrated in phantom line are expressly disclaimed and form no part of the claimed design.
